UNITED STATES PATENT OFFICE.

JORAM ZIEGLER, OF HARRISBURG, PENNSYLVANIA, ASSIGNOR TO ELLIOTT-FISHER COMPANY, OF NEW YORK, N. Y., A CORPORATION OF DELAWARE.

TALLY ATTACHMENT FOR TYPE-WRITERS.

1,146,382.

Specification of Letters Patent. Patented July 13, 1915.

Application filed October 13, 1906. Serial No. 338,785.

To all whom it may concern:

Be it known that I JORAM ZIEGLER, a citizen of the United States, residing at Harrisburg, in the county of Dauphin and State of Pennsylvania, have invented a new and useful Tally Attachment for Type-Writers, of which the following is a specification.

This invention relates to typewriting machines, but more particularly to a manifolding attachment therefor of the general character disclosed in a co-pending application of Clarence D. King and Andrew H. Milstead, filed May 5, 1905, Serial No. 258,925.

In the application above identified is shown a flat platen or book typewriter which, as is well understood in the art, includes a machine frame movable longitudinally of a flat platen to line space the writing and carrying printing or writing mechanism which is movable transversely of the platen to letter space the writing. At the front and rear of the frame are mounted carriers between which extends a tally sheet arranged to be printed upon by the writing mechanism when the latter is operating over a given area of the platen so as to produce a duplicate or tally record of a portion of the matter printed on a primary work sheet which is supported by the platen and extended beyond the secondary or tally sheet. A portion of the matter is printed directly on the primary work sheet, while that portion of which a tally is desired is printed directly on the tally sheet and is transferred to a subjacent work sheet, as for instance the primary sheet, by suitable transferring means. In the King and Milstead construction the mechanism which line spaces the machine over the platen also line spaces the tally sheet past the printing point of the machine and thus simultaneously effects the line spacing of the matter on both the tally and work sheets. The arrangement is such, however, that unless a spacing dog is moved to its inoperative position, the tally sheet is advanced whenever the machine is advanced, and this is undesirable for the reason that the machine is frequently advanced during the printing of that portion of the matter of which no tally record is desired, and the spacing of the tally sheet at such times merely results in the waste of space thereon.

The primary object of my invention, as distinguished from that of King and Milstead, is to provide line spacing mechanism

whereby, without special adjustment of any part of the mechanism, the line spacing of the machine will be effected, independently of the tally sheet, except when the machine is line spaced after the printing of an entry 60 on the tally sheet, so that no feed of the tally sheet, except such as is necessary to line space the entries thereon, will be effected.

Another object is to provide for the use of tally sheets or strips of various widths, 65 and in fact, to provide for the use of a strip or web substantially as wide as the work sheet so that, if desired, the manifolding of the entire matter printed can be effected, the original record being produced on the sheet 70 carried by the typewriter frame and the duplicate or copy record being transferred therefrom to a sheet carried by the platen.

Another object is to improve the mechanism for guiding, holding and feeding one 75 end of the web and to so arrange the receiving carrier that the printed portion of the web may be readily removed therefrom when desired.

Various objects of the invention, subordinate to those stated, will appear as the succeeding description is developed.

In the accompanying drawings, Figure 1 is a front elevation of an Elliott-Fisher typewriter equipped with my invention. 85 Fig. 2 is a detail view, showing the line spacing mechanism in end elevation and indicating one position of the tally sheet line spacing lever in dotted lines. Fig. 3 is a vertical section through the typewriter 90 frame and the tally sheet attachment, the carriage and certain of the mechanism carried thereby being indicated in dotted lines. Fig. 4 is a rear elevation of the machine 95 with the tally attachment applied. Fig. 5 is a plan view, partly in section, of the front portion of the typewriter frame and the adjacent elements of the attachment, the parts being broken away to facilitate their illustration. Fig. 6 is a front elevation, 100 partly in section, of that portion of the mechanism mounted at the front of the typewriter. Fig. 7 is a rear elevation, partly in section, of those elements of the attachment 105 which are located at the rear side of the typewriter. Fig. 8 is a sectional view on the line 8-8 of Fig. 5. Fig. 9 is a sectional view on the line 9-9 of Fig. 5. Fig. 10 is a section on the line 10-10 of Fig. 5. Fig. 11 is a detail view of the bracket for the sup- 110

port of the hold-back dog, and Fig. 12 is a detail view of the dog.

Referring to the reference characters on the drawings, 1 indicates the stationary flat platen of the Elliott-Fisher billing machine or typewriter of commerce. Along the longitudinal margins of this platen extend tracks or guides 2 which are toothed, as shown in Fig. 2, and portions of which are movable toward and from the platen to enable one or both of said tracks to act as a holder or clamp for the work sheet 3 imposed upon the writing surface of the platen. The tracks 2 support the machine frame 4, movable longitudinally of the platen to line space the typewriting accomplished by key-operated printing mechanism 5 supported by the carriage 6 and movable transversely of the platen on the frame 4 to letter space 20 the writing.

The carriage 6 is propelled by spring drums 7 and is controlled by the usual key-operated escapement mechanism. The inking ribbon 8 is mounted on the carriage and 25 extends under the type basket so that, when the type descends to the platen upon the operation of a key, the ribbon is interposed between the type and the work sheet 3 which is retained, as shown, in a flat spread-out 30 condition upon the platen.

The frame 4 is advanced step-by-step over the platen by the line spacing mechanism, which includes a spacing shaft 9 extending across the front of the frame 4 and carrying toothed pinions 10 meshing with the tracks or guides 2. The shaft 9 is afforded bearings in brackets 11, 12 and 13 projecting from the front of the frame 4. The brackets 12 and 13 are located at the right 35 hand end of the shaft and between them the shaft is provided with a knurled wheel 14 fixed to the shaft and a rocker arm 15 loose on said shaft. A line spacing lever or actuator 16 is pivoted at the free end of the 40 rocker arm 15 and is arranged to engage the rotary knurled wheel 14 on the shaft 9 to cause the pinions carried by said shaft to travel on the tracks and thus advance the machine frame.

50 A stop 17 limits the forward movement of the actuator, and a retracting spring 18 serves to retract the rocker arm and actuator after each line spacing operation. The throw of the line spacing lever or actuator 16 55 and thus the extent of the line space advance of the machine is regulated by a variable stop mechanism 19 which limits the return movement of the lever. The line spacing mechanism is that ordinarily employed on the Fisher machine and is exemplified in Patent No. 703,954, issued to R. J. Fisher July 1, 1902.

60 Mounted loosely on the shaft 9 and extending substantially the entire width of the writing surface of the platen is what may

be termed the lower or primary feed roll 20 having a rubber or other suitable frictional surface 21 and retained between a second rocker arm 22 loose on the shaft 9 and a set collar 23 fixed to the shaft at the opposite 70 end of the roll. Pivoted on the rocker arm 22 is a tally sheet line spacing lever or actuator 24 similar to the lever 16 and adapted to engage a second knurled wheel 25 fixed to the right hand end of the feed roll 20. The 75 forward movement of the actuator 24 is limited by a stop bar 26 the right hand end of which passes through the bracket 12 and projects beyond the same to form the stop 17. This actuator is retracted by a spring 80 27 similar to the spring 18, but having its fixed end secured to the bar 26, as shown in Fig. 8, as distinguished from the spring 18 the fixed end of which is carried by the bracket 13. Attention is directed to the 85 fact that each of the springs 18 and 27 has one end attached to a stud 28 or 28' extending from the adjacent rocker arm and serving to limit the slight relative movement of each actuator with respect to its arm, this 90 relative movement being necessary to permit the actuator to engage the adjacent knurled wheel when the actuator is drawn forward and to remain disengaged from the wheel during the retraction of the actuator. 95

It will now be seen that by the arrangement described, one of the line spacing levers may be operated to line space the machine over the platen and that the other lever may be operated to intermittently effect 100 rotary movement of the primary feed roll 20. Disposed above and in co-operative relation with the primary or lower feed roll 20 is an upper or secondary feed roll 29, preferably having a roughened or other form of frictional surface, as shown, and journaled at its opposite ends in vertically adjustable bearing blocks 30 guided in brackets 31 and prevented from rising by adjustment screws 32 retained in position by lock nuts 33. The 105 brackets 31 are held in spaced relation to the inner sides of the brackets 11 and 12 by bars 34, three bars being provided between each pair of brackets, and the stop bar 26 serving 110 as one of these in the connection of the brackets at the right hand side of the machine. 115

In advance of the primary feed roll 20 is supported the front carrier 35 for the tally sheet web, or strip 36, (see Fig. 3) led under the machine from the rear carrier 37, rotary guide rollers 38 and 39 being provided for the web at the bottom of the machine and adjacent to the front and rear sides of the frame 4, these rollers, like the feed rolls, extending substantially the entire width of the writing surface of the platen. The front carrier 35 is in the form of a 120 rotary spindle preferably having a knurled surface and is designed to have wound there- 125

on the front end of the tally sheet 36 which extends upwardly from the front guide 39 and thence between the feed rolls to the carrier 35. This arrangement results in the forward feed or advance of the tally sheet by the rotation of the primary feed roll which, through the medium of the paper, effects the rotation of the secondary feed roll and the front carrier 35, and causes the advanced portion of the tally sheet to be closely wound upon the latter.

As the front tally roll increases in size, it is necessary that the front carrier 35 shall recede from the primary feed roll, as indicated in dotted lines in Fig. 3. For this reason said carrier 35 is journaled in a swinging support comprising parallel arms 40 and 41 engaging the trunnions of the carrier, see Fig. 10, and fixed to a rock shaft 42 extending between the brackets 31, or more properly between extensions 43 and 44 of said brackets, see Fig. 5. The shaft 42 is journaled directly in the bracket 44 at one end, but its opposite end terminates at the inner face of the bracket extension 43 and is formed with an axial cavity 45 into which is extended a hollow journal 46 constituting an extension of the cap 47 secured in the bracket extension 43 by a set screw 48 and held against endwise movement by a nut 49 seated in a cavity in the end of the cap and engaging the threaded outer end of an axial stem 50 extended from the shaft 42.

Mounted in the space defined by the bores of the journal 46 and the shaft 42 conjointly is a spiral spring 51 one end of which is fixed to the shaft 42 and the other end of which is retained by the fixed cap 47. This spring exerts a constant tendency to rotate the shaft 42 in the proper direction to urge the front tally carrier 35 toward the primary feed roll. The spring 51 thus serves to yieldingly hold the carrier in coöperative relation to the feed roll, but is not of sufficient strength to unduly oppose the recession of the carrier from the feed roll as the tally sheet accumulates upon the former and thus increases the size of the front tally roll. Ordinarily, the printed portion of the tally strip is removed from the front carrier 35 by severing the strip at a point in rear of the carrier and then unwinding and removing the printed portion of the strip. It may be desirable, however, to retain the used portion of the strip in the form of a roll, as for instance to facilitate its transportation from the billing department of an establishment to the book-keeping department thereof. For this reason the arm 40 of the carrier support is retained upon the shaft 42 by a set screw 52, or other form of key, extended into a longitudinal groove 53 in the shaft 42. This character of mounting for the arm compels the latter to move with the shaft 42 when the latter is rocked, but per-

mits it to be moved longitudinally of the shaft for the purpose of withdrawing it from engagement with the trunnion of the carrier. The latter can thus be removed from its support and the tally roll slipped endwise therefrom; or, if desired, the machine may be provided with a number of carriers so that each carrier when filled may be removed with the tally roll and utilized as a core for the latter when the roll is unwound in the book-keeping or checking department.

The rear tally carrier 37 is in the form of a spool extensible to accommodate tally sheets of different widths and adjustable transversely of the platen to dispose it opposite any portion of the work sheet upon which the matter to be tallied is printed. It comprises a sleeve 54 carrying two independently adjustable disks 55 retained in their adjusted positions on the sleeve by set screws 56. The disks are thus relatively adjustable, according to the width of the tally strip to be employed. The sleeve 54 is mounted to rotate upon and is adjustable lengthwise of a shaft 57 extending entirely across the writing surface of the platen and supported above the latter by brackets 58 extended rearwardly from the frame 4 of the machine, see Figs. 3 and 7. At opposite ends of the sleeve 54 set collars 59 are adjustably retained on the shaft 57 by set screws 60, and between one of these collars and the adjacent end of the sleeve 54 is interposed a tension device, preferably in the form of a spring 61, which opposes sufficient frictional resistance to the rotation of the rear tally carrier to cause that portion of the tally sheet extending between the carriers to be held taut.

To facilitate the removal of the carrier 37 from the shaft 57, the latter is detachable from the brackets 58. At its left hand end the shaft 57 is provided with an extension 62 passed into the bracket 58 and held by a set screw 63. The other bracket, however, is provided with a latch 64 passed through the bracket 58 and into the hollow end of the shaft 57 and movable endwise to effect its withdrawal from the shaft in order to allow the right hand end of the latter to be moved laterally a sufficient distance to permit the displacement and replacement of the carrier. It will of course be understood that in order to permit this swinging movement of the shaft 57 when its right hand end is released, the fitting of the parts at the left hand end of the shaft will be somewhat loose, or, if desired, the shaft 57 may be moved laterally only a sufficient distance to permit it to clear the bracket 58 at the left hand side of the machine, the shaft being then withdrawn endwise from the other bracket.

It will now be seen that since the guide

rollers, the feed rolls and the front carrier all extend practically the entire width of the platen, and since the rear carrier is variable in size and adjustable to various positions transversely of the platen, it is possible to utilize tally sheets or strips of various widths and to effect the mounting thereof at various points, according to the location of the particular portion of the work sheet opposite which it is desired to locate the strip. As thus far described, the machine will be seen to comprehend a tally attachment including line spacing mechanism separate and distinct from the line spacing mechanism of the machine, so that the machine may be line spaced without necessarily effecting the line spacing of the tally sheet. One of the primary objects of my invention, however, is to establish a co-operative relation between the tally sheet line spacing mechanism and the machine line spacing mechanism so that, while the machine will be line spaced independently of the tally sheet when writing upon the primary work sheet alone, the line spacing of the tally sheet, after each entry thereon, will be accompanied by the line spacing of the machine, a single operation being necessary to effect the simultaneous line spacing of both the machine and the tally sheet. To attain this end, the rocker arm 22 of the tally sheet line spacing mechanism is provided with a laterally extended end 22' disposed in rear of the actuator 16 of the machine line spacing mechanism. Thus, while the lever 16 may be operated to independently advance the machine, the operation of the lever 24, to line space the tally sheet, will cause the lateral end of the arm 22 to simultaneously operate the lever 16, thus accomplishing the line spacing of the machine as the tally sheet is line spaced. In other words, the arrangement is such that when the lever 16 is operated, it will operate alone to effect the line spacing of the machine only, while the operation of the lever 24 will serve to operate the tally sheet feeding mechanism and also the machine line spacing mechanism to effect the simultaneous advance of both the tally sheet and the machine. It is not impossible, however, to line space the tally sheet without line spacing the machine, since, by holding the lever 16 of the machine line spacing mechanism in its advanced position, as shown in Fig. 2, the lever 24 of the tally spacing mechanism may be repeatedly operated without effecting line spacing of the machine, as for instance, when it is desired to complete the winding of the printed portion of the tally sheet upon the front carrier preparatory to detaching and removing said portion from the machine.

To prevent reverse rotation of the feed rolls when the rocker arm is retracted, a hold-back or check dog 65 is pivotally

mounted on a bracket 66 secured in any suitable manner to one of the rods 34. The dog has a knurled face 67 which is normally held in engagement with the knurled wheel 25 by a spring 68 having a bowed portion 70 which co-operates with a pin 69 projecting from one side of the dog, see Fig. 8. It is sometimes desirable, however, to permit reverse rotation of the feed rolls during the adjustment of the tally sheet, and the hold-back dog 65 is therefore provided with a knob 70 by means of which it may be swung out of engagement with the knurled wheel and retained in such inactive position by the spring 68, it being obvious that the bowed portion of the latter will, by engagement with the pin 69, effect the retention of the hold-back dog in either its active or inactive position.

It is thought that from the foregoing, the construction, operation, and advantages of my tally sheet attachment will be fully comprehended; but while the present embodiment of the invention is thought at this time to be preferable, I wish to be understood as reserving the right to make such changes, modifications and variations of the illustrated structure as may come fairly within the scope of the protection prayed.

What I claim is:—

1. A manifolding device including means for retaining work sheets in superposed relation, and separate line spacing mechanisms for said sheets, said line spacing mechanisms being co-operatively related to permit their 100 conjoint action and one of said line spacing mechanisms being operative independently of the other.

2. A manifolding device including means for retaining work sheets in superposed relation, and line spacing mechanism including line spacing actuators one of which is operative to effect line spacing of the writing on an inner sheet without effecting line spacing of the writing on the outermost 110 sheet the other of which is operative to effect line spacing of the writing on the several sheets.

3. In a typewriter, a platen and printing mechanism, means for retaining a plurality of superposed work sheets opposite the platen, and line spacing mechanism including two manually operated actuators for effecting the line spacing of the printing on an inner sheet alone or on both inner and 120 outer sheets simultaneously.

4. In a typewriting machine, a platen and printing mechanism, means for retaining a plurality of work sheets in superposed relation opposite the platen, line spacing mechanism including a plurality of actuators, and means establishing a co-operative relation between said actuators to secure their coaction.

5. In a typewriting machine, a platen and

- printing mechanism, machine line spacing mechanism operative to effect relative movement of the platen and printing mechanism, a work sheet movable relative to the printing mechanism, separate line spacing mechanism for said sheet, and means whereby the sheet line spacing mechanism will be caused to operate the machine line spacing mechanism.
6. In a typewriting machine, a platen and printing mechanism, machine line spacing mechanism operative to effect relative movement of the platen and printing mechanism, means for retaining a work sheet which sheet is movable relative to the printing mechanism for line spacing, line spacing mechanism for said sheet, separate actuators for the line spacing mechanisms, one of said actuators being operative independently of the other, and means for establishing a co-operative relation between the actuators to cause one to operate the other.
7. In a typewriting machine, a platen and printing mechanism, means for holding a work sheet opposite the platen, separate means for holding a superposed work sheet which sheet is movable relative to the printing mechanism in the direction of line spacing, machine line spacing mechanism operative to effect relative movement of the platen and printing mechanism, and separate sheet line spacing mechanism for advancing the superposed sheet.
8. In a typewriting machine, a platen and printing mechanism, means for holding a work sheet opposite the platen, separate means for holding a superposed work sheet which sheet is movable relative to the printing mechanism in the direction of line spacing, machine line spacing mechanism operative to effect relative movement of the platen and printing mechanism, separate sheet line spacing mechanism for advancing the superposed sheet, and means for causing one of said line spacing mechanisms to operate the other.
9. In a typewriting machine, a platen and printing mechanism, holders retaining a plurality of work sheets in position to be printed upon, machine line spacing mechanism operative to advance the printing mechanism relative to the platen, and sheet line spacing mechanism operative to advance one of the work sheets relative to the printing mechanism.
10. In a typewriting machine, a platen and printing mechanism movable thereover, means for retaining a work sheet on the platen, separate means for retaining a superposed sheet, machine line spacing mechanism operative to advance the printing mechanism over the platen in the direction of line spacing, sheet line spacing mechanism operative to advance one of the work sheets relative to the printing mechanism,
- and means for causing one of said line spacing mechanisms to operate the other, said means being arranged to permit one of said mechanisms to operate independently of the other.
11. In a typewriter, a platen, printing mechanism movable thereover, means for retaining a plurality of work sheets in position to be printed upon, and line spacing mechanism including two actuators one of said actuators being operative to advance the printing mechanism over the platen in the direction of line spacing and the other of said actuators being operative both to advance the machine in the manner stated and to advance one of the work sheets relative to the printing mechanism.
12. In a typewriter, a platen and a machine frame which are relatively movable, and printing mechanism, work holders for retaining a plurality of work sheets in position to be printed upon, one of said holders being mounted on the machine frame, line spacing mechanism for the sheet retained by the holder on the machine frame, and separate line spacing mechanism operative independently of the line spacing mechanism first named to effect relative movement of the platen and printing mechanism.
13. In a typewriter, a platen and a machine frame which are relatively movable, and printing mechanism, work holders for retaining a plurality of work sheets in position to be printed upon, one of said holders being mounted on the machine frame, line spacing mechanism for the sheet retained by the holders on the machine frame, separate line spacing mechanism operative independently of the line spacing mechanism first named to effect relative movement of the platen and printing mechanism, and means whereby one of said line spacing mechanisms may be operated by the other.
14. In a typewriting machine, the combination with a flat platen, of a frame mounted to travel thereover, printing mechanism on the frame, means for retaining a work sheet which is movable over the platen with the frame and disposed to be written upon by the printing mechanism, and mechanism including separate line space actuators one of which is operative to advance the machine frame over the platen and the other of which is operative to advance the work sheet relative to the printing mechanism.
15. In a typewriting machine, the combination with a flat platen, of a frame mounted to travel thereover, printing mechanism on the frame, means for retaining a work sheet which is movable over the platen with the frame and disposed to be written upon by the printing mechanism, and mechanism including two line space actuators one of which is operative to advance the machine frame over the platen and the

other of which is operative both to advance the machine frame over the platen and to advance the work sheet relative to the printing mechanism.

5 16. In a typewriting machine, the combination with a flat platen, of a frame mounted to travel thereover, printing mechanism on the frame, means for retaining a work sheet which is movable over the platen with 10 the frame and disposed to be written upon by the printing mechanism, mechanism including separate actuators one of which is operative independently to advance the machine frame over the platen and the other 15 of which is operative to advance the work sheet relative to the printing mechanism, and means for causing the last named actuator to operate the other.

17. In a typewriting machine, the combination with a flat platen, of printing mechanism movable thereover, machine line spacing mechanism, means for causing a work sheet to move with the printing mechanism, line spacing mechanism for said work sheet, 25 and means operated by said sheet line spacing mechanism for causing the printing mechanism to be advanced over the platen.

18. In a typewriting machine, the combination with a platen and a machine frame 30 mounted to travel thereover, and printing mechanism mounted on the frame, of sheet line spacing mechanism and machine line spacing mechanism both mounted on the machine frame and including adjacent actuators arranged for manual actuation one 35 independently of the other, and means operated by one of the actuators for moving the other.

19. In a typewriting machine, a platen 40 and printing mechanism, rotary delivering and receiving members between which a paper web is extended in position to be printed upon, feed rolls between which the web is passed, one of said rolls being in co-operative relation to the receiving member to cause rotation of the latter and the winding of the web thereon, and means for operating the feed rolls.

20. In a typewriting machine, a platen 50 and printing mechanism, a pair of paper feeding rolls between which a paper web is led, and means for operating said rolls and for simultaneously effecting relative movement of the platen and printing mechanism 55 in the direction of line spacing.

21. In a typewriting machine, the combination with a platen and printing mechanism, of paper feeding mechanism, two actuators arranged for manual actuation, one 60 independently of the other, and means whereby the operation of one actuator will serve to effect relative movement of the platen and printing mechanism independently of the paper feeding mechanism and 65 whereby the operation of the other actuator

70 will cause the operation of the paper feeding mechanism and also relative movement of the platen and printing mechanism.

22. In a typewriting machine, the combination with a flat platen, of a frame mounted to travel thereover, printing mechanism on the frame, paper delivering and receiving members mounted on the frame, and paper feeding mechanism intermediate of 75 said members.

23. In a typewriting machine, the combination with a flat platen, of a frame mounted to travel thereover, printing mechanism mounted on the frame, rotary carriers mounted on the frame to deliver and receive a web extended between said carriers, 80 paper feeding rolls carried by the frame adjacent to the receiving carrier, and means for operating the rolls.

24. In a typewriting machine, the combination with a platen and printing mechanism, of paper feeding mechanism, means for operating said paper feeding mechanism, a receiving member upon which the advanced end of the paper is wound, means 85 for supporting the receiving member for movement into and out of co-operative relation with the feeding mechanism.

25. In a typewriting machine, the combination with a platen and printing mechanism, of delivering and receiving members for the paper web, web feeding mechanism, and a swinging support retaining one of 90 said members in position to be operated by the web feeding mechanism.

26. In a typewriting machine, the combination with a flat platen, of a frame mounted to travel thereover, printing mechanism on the frame, a swinging support on the frame, and a paper carrier mounted on the 105 support.

27. In a typewriting machine, the combination with a flat platen, of a frame mounted to travel thereover, printing mechanism on the frame, and paper delivering and receiving carriers also mounted on the frame, 110 one of said carriers being adjustable in a direction parallel with the lines of writing.

28. In a typewriting machine, of a platen and printing mechanism, a pair of paper feeding rolls and a receiving member, said rolls and member extending substantially the width of the platen, and a paper carrier arranged to deliver a paper web to the 115 feeding rolls and receiving member and between the platen and printing mechanism, said carrier being of materially less width than the platen and adjustable in a plane parallel with the feeding rolls.

29. In a typewriting machine, the combination with a flat platen, of a frame mounted to travel thereover, printing mechanism on the frame, a paper delivering carrier mounted on the frame in rear thereof and 120

130

laterally adjustable, and a paper receiving member mounted on the frame at the front side thereof and extending substantially the width of the platen.

- 5 30. In a typewriting machine, the combination with a flat platen, of a frame mounted to travel thereover, printing mechanism on the frame, a paper delivering carrier mounted on the frame in rear thereof and laterally adjustable, a paper receiving member mounted on the frame at the front side thereof and extending substantially the width of the platen, and paper feeding rolls also mounted on the frame.
- 15 31. In a typewriting machine, the combination with a flat platen, of a frame mounted to travel thereover, a shaft carried by said frame, an extensible spool adjustable on the shaft, and means also mounted on the frame for engaging and holding the end 20 of a paper web delivered from said spool.

32. In a typewriting machine, the combination with a platen and printing mechanism, of means for retaining two work sheets in superposed relation, and line spacing mechanism operative to effect either of three classes of feed, to-wit; to effect relative movement of the platen and printing mechanism to line space the writing on one 30 only of the work sheets; to effect the independent advance of the other work sheet relative to the printing mechanism in the direction of line spacing; to effect relative movement of the printing mechanism and 35 both work sheets to simultaneously effect line spacing of the writing on both sheets.

33. In a typewriting machine, the combination with a platen and printing mechanism, of paper feeding mechanism, two actuators arranged for manual actuation one 40 independently of the other, means whereby the operation of one actuator will serve to effect relative movement of the platen and printing mechanism independently of the 45 operation of the paper feeding mechanism,

and means whereby the operation of the other actuator will cause the operation of the paper feeding mechanism and also relative movement of the platen and printing mechanism.

50

34. In a type-writing machine, the combination with a platen and printing mechanism, of means for retaining a plurality of work sheets, a plurality of line spacing mechanisms, one operative independently of another, and one of said line-spacing mechanisms arranged to operate another, and a plurality of manually operated actuators for said line-spacing mechanisms.

35. In a typewriting machine, a platen 60 and printing mechanism, machine line spacing mechanism operative to effect relative movement of the platen and printing mechanism, a work sheet movable relative to the printing mechanism, separate line spacing 65 mechanism for said sheet and means whereby one of said line spacing mechanisms will be caused to operate the other.

36. In a typewriting machine, a platen and printing mechanism, means for holding 70 a work sheet opposite the platen, separate means for holding a second work sheet which is movable relative to the printing mechanism for line spacing and separate line spacing mechanisms, one of which effects 75 relative movement of the platen and printing mechanism to line space the writing on the first sheet and to advance the second work sheet relative to the first work sheet and the other of which effects relative line 80 spacing movement of the printing mechanism and the second work sheet.

In testimony, that I claim the foregoing as my own, I have hereto affixed my signature in the presence of two witnesses.

JORAM ZIEGLER.
